UNITED STATES PATENT OFFICE.

JOSEPH A. SEGUIN, OF WINNIPEG, MANITOBA, CANADA.

SECURING DEVICE FOR BOXES.

Application filed December 22, 1925, Serial No. 77,034. Renewed June 25, 1927.

The object of this invention is to provide special means for securing the cover of a box or crate designed for shipping soft drinks, eggs, or other articles of produce, when the container is of sufficient value to justify return to the shipper for refilling, or when it is desired to store the covers separately.

The securing device may be manufactured in different sizes and may have connection with the cover, as shown in Figure 1, or may be freely mounted as in Figure 2, and retained by the tension exerted by the locking means, or may have the sides of the lower U-frame or strap secured by bolting, as in Figure 3.

With the foregoing and other objects in view, the invention consists in the novel construction and arrangement of elements described, illustrated and claimed, it being understood that modifications may be made within the scope of the claims without departing from the spirit of the invention.

In the drawings forming part of this application:

Figure 1 is a perspective view showing a box or crate conventionally, and showing my attachment or securing device applied thereto.

Figure 2 is also a perspective view, showing the top and rear portion of the container and the attachment in position thereon, there being no direct connection between the attachment and the cover.

Figure 3 shows the container in vertical transverse section, the attachment being in position and being secured by bolts or the like.

Figure 4 is a perspective view of the locking means.

Figure 5 is a top plan view of the locking means with a portion in section,—a portion of the front wall of the container also being in horizontal section.

In the several views the box or crate is designated 10, and is provided with a cover 11 adapted to fit the container without being secured thereto until the attachment or locking device herein described is applied. This permits the separation and storage of the covers separately when desired.

The securing device as a whole comprises an upper element of U-shape, a rear element pivotally connected therewith and forming a yoke or the like, the U-shaped strap adapted to pass under the bottom of

the container and to extend upwardly along the front and rear walls thereof,—the attachment further including the particular locking means illustrated in Figure 4.

The upper U-shaped frame 12 may be of about the form shown, that is, provided with a deflected portion 13 at the middle and front portion, and provided with eyes 14 at the rear ends, these eyes receiving the bent over end portions 15 of yoke 16 having connection with the rolled end 17 of a plate 18 having a key hole slot 20 therein. The bottom element, comprising a U-shaped frame or strap 25, extends across the bottom and thence upwardly along the front and rear walls. A pin 26 is carried by one arm or side portion of frame 25 and is adapted to pass through the key hole slot 20 of plate 18, the tension produced by the locking means described below holding the parts in locking engagement.

A lever 28 is mounted on the front portion of frame or strap 25 by means of a pivot 29, and this lever has pivotal connection at 30 with a tubular element 31 having a threaded bore 32 receiving the threaded end of a hasp or the like, designated 34. This element 34 has a hook 35 formed on its upper end, the hook being designed for engagement with the middle portion 13 of upper U-frame 12, in the manner illustrated especially in Figures 1 and 3. The threads between elements 31 and 34 permit of adjustment and of securing proper tension on the locking means when the lever 28 is thrown to the position of Figure 1. Lever 28 has an offset end 37 constituting an ear and provided with an aperture 38 therein, and also provided with an offset 39. The portion last named contacts with the end of a link 40 shown in top plan in Figure 5 and in perspective in Figure 4, and also appearing in Figure 1. This link 40 includes an eye portion 41 through which the element 34 passes, and member 40 further includes an aperture 42 adapted to register with aperture 38 in the offset end of the lever 28, so that a seal of usual commercial type, designated 44, may be employed for sealing the lock when the elements thereof have been placed in the position of Figure 1.

Having thus described the invention, what is claimed as new, is:—

1. A device of the class described, comprising a U-shaped member adapted to pass beneath a container and to extend upwardly

along the front and rear walls thereof, a second U-shaped member detachably connected with that first named, and extending across the back of the container, a frame to be secured to the top of the container and having hinge connection with the second U-shaped member, and means for detachably connecting the frame secured to the top with the first named U-shaped member.

2. A device of the class described, comprising a plurality of U-shaped members adapted to pass around the bottom, top, front and rear of a container, two of said members being movably connected to form a hinge for the top, and a pivotally mounted hook connected with one of the U-shaped members and adapted to detachably connect the same with an adjacent U-shaped member.

3. A device of the class described, comprising movably connected members adapted to pass around four sides of a container, a lever pivotally mounted on one of the members and including an offset end, and a hook pivoted on the lever and eccentric with reference to the pivotal mounting of said lever, the hook being adapted to engage one of the members first named and to be tensioned by the lever, and means for securing the lever and hook against operation by unauthorized individuals, said means including an element 30 slidable on the hook and cooperating with the offset end of the lever, and a retaining device engaging the slidale element and offset end.

Winnipeg, Canada, December 5th, 1925.
JOSEPH A. SEGUIN.
